UNITED STATES PATENT OFFICE.

CHRISTOPHER J. MEYER, OF MILWAUKEE, WISCONSIN, ASSIGNOR TO EVINRUDE MOTOR COMPANY, OF MILWAUKEE, WISCONSIN, A CORPORATION OF WISCONSIN.

TRANSOM-CLAMPING BRACKET.

1,236,735.

Specification of Letters Patent. Patented Aug. 14, 1917.

Application filed March 22, 1915. Serial No. 16,143.

To all whom it may concern:

Be it known that I, CHRISTOPHER J. MEYER, a citizen of the United States, residing at Milwaukee, county of Milwaukee, 5 and State of Wisconsin, have invented new and useful Improvements in Transom-Clamping Brackets, of which the following is a specification.

My invention relates to improvements in 10 transom clamping brackets for detachable row boat motors.

The transoms of row boats vary in form and are frequently more or less warped or 15 irregular in surface contour. On the other hand, detachable row boat motors are designed to be conveyed from place to place and secured to different row boats at different times.

The object of my invention therefore is 20 to provide a form of clamp which will engage any style of transom and which will facilitate binding the motor driven propelling mechanism thereto with absolute rigidity notwithstanding irregularities in the 25 form of the transom or in its surface contour.

In the drawings—

Figure 1 is a perspective view of a detachable row boat motor provided with a transom clamp embodying my invention. 30

Fig. 2 is a detail front elevation of the transom clamp showing a fragment of a transom engaged thereby.

Fig. 3 is a side elevation with a fragment 35 of an engaged transom clamp illustrated in section.

Like parts are identified by the same reference characters throughout the several views.

40 My improved transom bracket is organized with a view to securing a three point bearing upon the rear face of the transom and clamping bearings at two points upon the front face of the transom, the clamping 45 bearings being preferably so located as to substantially equalize the pressure at each of the three points where bearing is had upon the rear or outer transom face. The head A of the bracket is adapted to rest 50 upon the top of the transom in the usual manner and is provided with upwardly projecting posts B, suitably apertured to receive the connecting bolts C, whereby the bracket may be connected with the motor 55 frame. The rear portion of the head is

provided with a pair of arms, which extend downwardly from the respective sides and convergingly at their lower ends to a lower clamping plate C' having a knurled engaging inner face. The upper end of each of these arms has a bearing portion D, adapted to engage the transom E near the upper margin of the latter, the said bearing portions being extended inwardly and connected together forming with the inner face of the head A a right angular seat for resting upon the transom edge. Below the bearing members D, each of the arms is offset rearwardly out of contact with the transom E, as indicated at F. The converging lower 70 end portions F' of the arms have an angular forward pitch and support the bearing member C' in position to engage the transom E simultaneously with the engagement of the portion D. 75

It will be observed that the two upper bearing portions D and the lower bearing portion C' are at the respective angles of an approximately equilateral triangle and the bracket will therefore automatically adjust itself to the contour of the rear face of the transom, when applied thereto in the position illustrated in Figs. 2 and 3. The downwardly projecting arms are preferably provided with rearwardly projecting reinforcing webs G, whereby sufficient rigidity is imparted to the arms without excessive weight. A pair of segmental arms H extend rearwardly from the member C' and are adapted to engage a supporting block 90 I, whereby the propeller supporting shaft J may be held in a vertical position. The members I and J, however, form no part of the present invention and are not claimed herein. 85

95 The front portion of the bracket head A is provided with a pair of forwardly and downwardly projecting arms K with which clamping set screws L have threaded engagement adjacent the free ends thereof, 100 which ends are connected together by a brace N which is parallel with the said head A. These set screws are provided with ordinary swivel heads M adapted to bear upon the inner or front face of the transom. It will be observed that the clamping heads M engage the transom below the points engaged by the bearing members D. The pressure exerted by the clamping heads M is along 105 lines which, if projected, would intersect 110

the offset portions F of the rear clamping arms. The specific position of the clamping heads M, however, is not essential to my invention, except that it is very desirable 5 that they be so located as to distribute the pressure upon the three rear bearing points.

I claim—

1. A transom clamping bracket for boats comprising a head adapted to rest upon the 10 top of the transom, opposite upright reinforced posts upon said head adapted for pivotal connection with a boat propelling motor, a pair of arms extending downwardly and convergingly from the opposite sides of 15 the head, a substantially rectangular clamping plate connecting the lower ends of the said arms having a knurled inner engaging face, and a set of clamping set screws supported from the head in a position to engage 20 the transom between said screws and arms, the said arms being provided with bearing portions adjacent their upper ends connected together inwardly angularly disposed with respect to the inner face of the said 25 head and adapted to engage the side of the transom when the device is operatively positioned, the said arms being offset from the transom between said clamping plate and bearing portions, the said set screws having 30 swiveled clamping heads located to substantially equalize the pressure upon the bearing portions of said arms and upon the said clamping plate.

2. A clamping bracket, including the com-

bination of a head portion having a rear pair 35 of depending arms arranged to engage the upper marginal portion of the transom on the rear side, and offset therefrom below the points of engagement, the lower portions of said arms converging downwardly, a clamping plate connecting the lower ends of said arms, and adapted to bear upon the middle portion of the boat transom, a forward pair 40 of relatively short arms depending from the head out of contact with the transom, set 45 screws at the lower ends of said forward arms projecting rearwardly in the direction of the transom, and provided with clamping plates adapted to engage the front surface of the transom at points above and laterally 50 offset from the area engaged by the first mentioned clamping plate on the rear surface of said transom, whereby when the set screws are turned to clamping position the rear face of the transom will be engaged at 55 three bearing points, and the front face will be engaged at two bearing areas, with the front bearing area disposed intermediate of the upper and lower bearing areas of the 60 rear arms to equalize and distribute the bearing pressures, substantially as described.

In testimony whereof I affix my signature in the presence of two witnesses.

CHRISTOPHER J. MEYER.
